UNITED STATES PATENT OFFICE.

JOHN H. DE SMIDT, OF MINNEAPOLIS, MINNESOTA.

WINDOW SCREEN.

Application filed June 22, 1922. Serial No. 570,243.

To all whom it may concern:

Be it known that I, JOHN H. DE SMIDT, a citizen of the United States, residing at Minneapolis, in the county of Hennepin and State of Minnesota, have invented certain new and useful Improvements in Window Screens; and I do hereby declare the following to be a full, clear, and exact description of the invention, such as will enable others skilled in the art to which it appertains to make and use the same.

My present invention relates to window screens and more particularly to screens of the type that are mounted on spring-actuated rollers and arranged to be drawn by a window, during its opening movement, across the opening thereof.

One of the objects of the invention is the reinforcing and stiffening of the longitudinal edge portions of the fabric mesh screen by applying thereto paint or other pliable material, which permits the cutting away of the selvage edges of the screen in trimming the same to fit windows of different widths. This treatment of the longitudinal edge portions of the screen prevents the same from unravelling or tearing and does not perceptibly increase the thickness thereof, which permits the screen to be wound onto a roller very evenly and in compact form. The stiffening of the longitudinal edges of a fabric screen greatly assists in causing the same to remain very close to a window frame and thereby form tight joints between the screen and said frame.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view in vertical section of upper and lower window sashes mounted in a frame to which the invention is applied;

Fig. 2 is a perspective view of the invention, with some parts broken away and sectioned, and also illustrating a portion of the lower window sash;

Fig. 3 is a detail view in section taken on the line 3—3 of Fig. 1;

Fig. 4 is a view corresponding to Fig. 1 with the exception that some parts have

been broken away, other parts removed, and showing the lower sash closed;

Fig. 5 is a view in central vertical section showing the lower window sash open and the screen detached from the frame and wound completely into the casing; and

Fig. 6 is a fragmentary perspective view of the window frame, and one of the joint strips attached thereto.

The numeral 7 indicates a window frame having an inner channel 8 and an outer channel 9, in which are mounted vertically sliding lower and upper window sashes 10 and 11, respectively. A fabric mesh screen 12 is wound onto a spring-actuated roller 13 mounted in a casing 14. This roller 13 is preferably of the type commonly used for mounting window shades and is equipped with trunnions 15 and 16 mounted in seats in the ends of the casing 14. The trunnion 15 is flattened and the seat therefor is correspondingly formed to hold said trunnion against rotation, for a well known purpose.

The casing 14 is attached, as shown, to the lower rail of the lower sash 10 and, at its front, is segmental in cross section and open at its back, which is closed by said lower rail. The top of the casing 14 extends tangentially inward and then upward to afford a flange 17 through which screws 18 are inserted to detachably connect said casing to the window sash. The bottom of the casing 14 terminates short of the back thereof to leave an entrance passageway 19 through which the screen 12 moves into and out of said casing. To fit the casing 14 to windows of different widths, the same is made in two sections and the inner end portions thereof overlap for sliding movement, the one upon the other. To hold the sections of the casing 14 against radial separation, in respect to the roller 13, the flange 17 and bottom of the outer casing section, at the entrance passageway 19, are formed with channels in which the flange and bottom portion of the other casing section are slidably mounted.

The two sections of the flange 17 are provided with longitudinally extended slots 20 arranged to be successively brought into coincident relation to receive therethrough a screw 21, which further connects the two sections of the casing 14 and secures the same to the sash. Interposed between the flange 17 and sash 10 are shims 22 held in

position by the screws 18 and provided to space the end portions of the casing 14 from the sash 10 to receive therebetween joint strips 23. These joint strips 23 have 5 outturned flanges 24 which bear upon the stops 25 between the sashes 10 and 11 and are secured thereto by screws 26.

On the lower edge of the screen 12 is a stiffening bar 27 that is U-shaped in cross-section to receive said screen between its flanges. These flanges of the stiffening bar 27 are pressed together to clamp the screen 12 therebetween. The outer end portions of the outer flange of the stiffening bar 27 are 15 turned outward at their upper end portions to afford outstanding stop flanges 28 arranged to engage the bottom of the casing 14 to prevent the stiffening bar 27 from being drawn completely into the casing 14 under the action of the spring roller 15 when 20 said stiffening bar is detached from the frame 7.

To detachably secure the lower edge portion of the screen 12 to the window frame, 25 pins 29 are extended through the flanges 24 and anchored in the stops 25. These pins 29 are engaged by the flanges 28 and hold the lower edge portion of the stiffening bar 27 against the window sill 30. Preferably, 30 as shown in Fig. 2, the flanges 28 are transversely cut to divide the same into a multiplicity of sections, the purpose of which will presently appear. The stiffening bar 27 is further secured to the frame 7 by a hook 35 31 anchored in the window sill 30 and interlocked with an edge 32 in said stiffening bar, at the longitudinal center thereof.

The longitudinal edge portions of the screen 12 are painted or otherwise treated 40 with a pliable material, as indicated at 33, which fills the mesh therein and reinforces and stiffens said edge portions. The purpose of thus treating the longitudinal edge portions 33 of the screen 12 is to permit the 45 same to be trimmed, so that the screen 12 may be fitted to windows of different widths, and prevents the same from unravelling or tearing after the selvage has been cut away. This treatment of the longitudinal edge portions 50 33 also stiffens the same and causes said edge portions to lie close to the joint strips 23, which are overlapped thereby, as best shown in Fig. 3, to form tight joints. The filling of the mesh in the outer longitudinal edge portions 33, with paint or other 55 pliable material, does not perceptibly increase the thickness of the screen 12, so that the same will wind onto the roller 13 very evenly and in compact form. To hem the longitudinal edges of the fabric screen 12, to 60 prevent unravelling or tearing, would materially increase the thickness of the screen 12, at its longitudinal edge portions, and when wound onto the roller 13, would be 65 uneven and very bulky.

The purpose of transversely dividing the flange 28 is to permit one or more sections thereof to be broken off by a pair of pliers or other suitable tool, to facilitate the trimming of the longitudinal edges of the screen 7 12 and the ends of the stiffening bar 27 to fit windows of different widths.

When the lower sash 10 is closed, the screen 12 will be entirely enclosed in the casing 14 and protected from the weather. 7 When the sash 10 is open in various different positions, the opening of the window frame left by said sash will be closed by the screen 12 to exclude flies, mosquitoes, and various different insects, and dust and dirt, and, at 80 the same time, permit the desired ventilation. When the screen is not required, the anchored free end thereof may be released from the window frame by detaching the hook 85 31 from the eye 32 and drawing the stiffening bar away from the pins 29 sufficiently to permit folding of the screen 12 to clear said pins.

While the casing is shown attached to a lower sash and the screen anchored to a window sill, it is, of course, understood that a second casing could be attached to the upper sash and the screen anchored to the top of the window frame so that both windows could be opened, and the openings in the window frame left thereby closed by the respective screens.

Obviously, the spring roller keeps the screen taut and when the lower sash is lowered the screen automatically is taken up and wound on the roller. The stiffening bar 27, when the screen is wound entirely within the casing, affords a flashing to direct rain away from the casing.

What I claim is:

1. A fabric mesh screen having its outer edge portions painted to fill the mesh and stiffen the same.
2. The combination with a roller, of a screen attached to the roller, and having its outer edge portions painted to fill the mesh and stiffen the same.
3. The combination with a spring-actuated roller applicable to a window sash, of a screen attached to said roller and adapted to be wound thereon, and means for attaching the free end of said screen to a frame in which said sash is slidably mounted, the longitudinal edge portions of said screen being painted to fill the mesh and stiffen the same.
4. The structure defined in claim 3 in further combination with joint strips on the frame that are overlapped by the stiffened longitudinal edges of the screen.
5. The combination with a casing applicable to a window sash, of a spring-actuated roller mounted in the casing, a screen attached to said roller and adapted to be wound thereon, means for attaching the free

- end of the screen to a frame in which said sash is slidably mounted, the longitudinal edge portions of the screen being painted to stiffen the same, and joint strips on the frame that are overlapped by the stiffened longitudinal edges of the screen, the end portions of the casing being spaced from the window sash to leave clearance for the joint strips between the window sash and casing.
- 5 6. The combination with a casing applicable to a window sash and having an entrance passageway, of a spring-actuated roller mounted in the casing, a screen attached to said roller and adapted to be wound thereon, a stiffening bar on the free end of the screen, 15 said stiffening bar having at its ends outstanding flanges, and means on the frame with which said flanges engage to anchor the free end of the screen to the frame, said flanges having a multiplicity of transverse 20 divisions which permit sections thereof to be broken off and the stiffening bar cut to vary the length of said stiffening bar.
- In testimony whereof I affix my signature.

JOHN H. DE SMIDT.
